CLAIM

The ornamental design for a container protector, as shown and described.

DESCRIPTION

FIG. 1 is a first perspective view of a container protector according to the present invention;

FIG. 2 is a top plan view of the container protector;

FIG. 3 is a front elevation view of the container protector, the rear elevation view being a mirror image thereof;

FIG. 4 is a left side elevation view of the container protector, the right side elevation view being a mirror image thereof;

FIG. 5 is a bottom plan view of the container protector;

FIG. 6 is a second perspective view of the container protector;

FIG. 7 is a third perspective view of the container protector; and,

FIG. 8 is a fourth perspective view of the container protector.

1 Claim, 8 Drawing Sheets
